ALFRED CORBETT, OF IRWIN, PENNSYLVANIA, ASSIGNOR TO WESTINGHOUSE ELECTRIC & MANUFACTURING COMPANY, A CORPORATION OF PENNSYLVANIA

CONTACT FOR CHANNEL-BRUSH SWITCHES

Application filed August 6, 1927. Serial No. 211,041.

My invention relates to switch mechanism and particularly to panel switches having a rotary operating handle.

An object of my invention is to provide a panel board switch for controlling the main circuit of a distributing panel, wherein the switch is actuated by a rotary cam and wherein, the contact members of the switch engage the stationary contact terminals with a sliding and rolling action.

A further object of my invention is to provide a switch contact member wherein, the contact shoes are supported upon a laminar switch arm which is flexed when moved to closed position and thereby causes the contact shoes to yieldingly engage the contact terminals with a rubbing action which serves to clean the contact shoes and terminals.

These and other objects that are made apparent throughout the further description of my invention are attained by the apparatus hereinafter described and illustrated in the accompanying drawings, wherein:

Figure 1 is an elevational view of switch apparatus embodying features of my invention, the casing therefore, being shown in section, and

Fig. 2 is a transverse section through the apparatus taken on the line I—II of Fig. 1 showing the switch contact elements in plan view.

Referring to the drawings, the apparatus comprises a housing 3 in which an insulating base 4 is mounted. Contact terminals 5 are mounted upon the insulating base 4 and extend through insulating bushings 6 in the side walls of the housing.

A switch carrier 7 is slidably mounted upon studs 8 that are secured at their inner ends to the insulating base 4, the carriers being yieldingly maintained in open position by means of springs 9 that surround the studs 8 and which are disposed between the carrier 7 and the insulating base.

As illustrated, the switch is of the 3 pole type, there being 3 sets of contact terminals 5 that are adapted to be connected by the bridging switch arms mounted on the carrier 7. Each switch arm comprises a laminar member 11 made of phospher-bronze lam-

inae, or strips that are secured in assembled position upon the carrier by means of rivets 12. Contact shoes 13 are secured to the lowermost lamination of the bridging switch, the shoes having convex contact surfaces 14 that are adapted to engage the contact terminals 5 with a rolling and sliding movement in order to clean the surface of the contact shoes and the contact terminals at each operation of the switch. The upper-most lamination 15 of the switch arm 11 is of greater length than the remaining laminations and is provided with arcing tips 16 that also engage the contact terminals 5 in such manner that they are first to make contact with the contact terminals 5 and last to break contact therewith, thus causing the arc, incident to the separation of the contacts, to be drawn by the arcing tip 16 at a point on the contact terminals 5 remote from the point of contact of the shoes with the contact terminals 5.

The carrier 7 is provided with a pair of rollers 17, which engage the edges of a rotary cam 18 having inclined cam surfaces 19. As shown in the drawings, the cam 18 is pivoted for rotation upon a pin 21 that is pivotally mounted upon a cover plate 22 secured to the housing 3. As shown in Fig. 1, the switch is in its closed position and the roller 17 is seated in a slight depression 23 in the cam face 19. The switch is thus releasably held in closed position.

When the operating handle 24, which is connected to the cam member 18 by a lost motion connection, is rotated in a counter-clockwise direction, the springs 19 will force the roller along the inclined cam surface 19 to the open position with a snap action. To close the switch, the operating handle is moved in a clockwise direction, thus causing the cam surface 19 to force the carrier 7 downward into the closed position, shown in Fig. 1.

The construction is simple and contains relatively few parts and is, therefore, inexpensive to manufacture. A conductive contact is secured each time the switch is closed and relatively high pressures may be exerted upon the contacts with a minimum of effort, due to the cam action of the operating handle. A particular advantage of the construction is

the absence of heating of the switch parts usually present in contact switches of the butt contact type.

While I have illustrated but one embodiment of my invention, it will be apparent to those skilled in the art that various changes, modifications, substitutions, additions and omissions may be made in the apparatus illustrated without departing from the spirit and scope of my invention as set forth in the appended claims.

I claim as my invention:

1. A switch comprising a pair of spaced contact members, and a movable switch member comprising a carrier, a yielding laminar member mounted on the carrier and extending transversely of the direction of movement of the carrier and comprising a plurality of separate flexible plates, contacts mounted on the free ends of the undermost plate having convex contact surfaces for engaging the contact members with a sliding and rolling movement, and means for moving the carrier to closed position, wherein the laminar member is flexed and yieldingly presses the contacts into engagement with the contact member.
2. A switch comprising a pair of spaced contact members, a movable switch member comprising a carrier, a yielding laminar member mounted on the carrier and extending transversely of the direction of movement of the carrier, contacts mounted on the free ends of the undermost lamination having a pair of contact shoes provided with convex contact surfaces for engaging the contact members with a sliding and rolling movement, the uppermost lamination of the laminar member being longer than the others and being provided with an arcing tip, and means for moving the carrier to closed position wherein the contact shoes are yieldingly maintained in contact with the said contact members.

In testimony whereof, I have hereunto subscribed my name this 3rd day of August, 1927.

ALFRED CORBETT.
